CLAIM

The ornamental design for a prosthetic torque wrench, as shown and described.

DESCRIPTION

FIG. 1 is a perspective view showing the new design for the prosthetic torque wrench;

FIG. 2 is a front view of the prosthetic torque wrench;

FIG. 3 is a back side view of the prosthetic torque wrench;

FIG. 4 is a left side view of the prosthetic torque wrench;

FIG. 5 is a right side view of the prosthetic torque wrench;

FIG. 6 is a top view of the prosthetic torque wrench; and,

FIG. 7 is a bottom view of the prosthetic torque wrench.

The broken lines are included for the purpose of illustrating portions of the prosthetic torque wrench that form no part of the claimed design.

1 Claim, 7 Drawing Sheets
